UNITED STATES PATENT OFFICE.

JAMES A. CHARTER, OF CHICAGO, ILLINOIS.

COMBINED FURNACE AND GAS-GENERATOR THEREFOR.

1,128,584.

Specification of Letters Patent. Patented Feb. 16, 1915.

Application filed November 11, 1912. Serial No. 730,784.

To all whom it may concern:

Be it known that I, JAMES A. CHARTER, a citizen of the United States, residing at Chicago, in the county of Cook and State of Illinois, have invented a certain new and useful Combined Furnace and Gas-Generator Therefor, of which the following is a specification.

Crude oil has until very recently been the most economical fuel for creating an intense heat in furnaces, ovens and the like.

The object of this invention is to provide a device for fueling such devices, in which coal, peat and other similar fuels in more or less pure form are used, and which in the process of burning the coal is converted into gas, which with the resulting coke is consumed in the furnace, oven, or other heat generators to which the device of this invention is applied.

This invention consists in a mechanism capable of carrying out the foregoing objects which can be very easily and cheaply made and installed, which is satisfactory in operation and not readily liable to get out of order.

More in detail the invention consists broadly in a device by which coal is heated by the furnace in which it is to be burned and converted into gas which is later conveyed into the furnace together with the coke and other waste products of the coal, created in the production of the gas and there burned.

Other features and details of the invention will be fully explained later in the specification.

In the drawings Figure 1 is a sectional elevation of a furnace having one form of this invention applied thereto. In this figure a belt mechanism is shown for operating the device for forcing the coal across the interior of the furnace. Fig. 2 is a view identical with Fig. 1, showing a motor, preferably steam operated, taking the place of the belt mechanism of Fig. 1. Fig. 3 is a plan and Fig. 4 a front view of a modified form of the device in which the coal is conveyed across the corners of the furnace. Fig. 5 is a front view of a modified form of construction in which chains are used for feeding the coal through the furnace.

In all of the figures the similar numerals indicated denote similar parts throughout the several views.

In all of the figures a conventional form of furnace, oven, or the like 10 is shown in which the fuel is ultimately to be burned. In the operation of all of the devices a fire is started in the furnace chamber or fire box 12 by the use of kindling or other suitable material and maintained a sufficient length of time to heat up the device and start the production of gas in the manner hereafter described, after which this initial fire may be allowed to die out and the device operates automatically thereafter so long as coal is supplied to the hopper 14. This coal hopper is in each instance, located at one side of the furnace near its top, and is provided with a suitable opening 16 through which coal or other material to be operated upon may be introduced. This opening is closable by means of a lid 18 securable in tight position by the use of a screw or clamp device 20 of ordinary construction.

In the construction shown in Fig. 1, one or more pipes 22 enter the lower portion of the coal hopper 14 and thence extend entirely through both walls and the fire chamber of the furnace, so that fire within the furnace comes in contact with the central portions of these pipes. The opposite ends of the pipes 22 terminate in a receptacle 24 having a hollow chamber 34 therein closed at its top with a valve or cap 24 and having its lower ends opening into an injector 26 whose nozzle 28 enters the fire chamber 12 of the furnace, preferably below the pipes 22. This injector 26 is fitted with a steam or air nozzle 30 controlled by a valve 32 in the ordinary manner. The construction is, like all devices of this kind, such that when gas is delivered by the tubes 22 into the interior chamber 34 of the receptacle 24 and steam or air is admitted through the nozzle 30, the gas or fuel within the space 34 will be driven through the nozzle 28 into the furnace. The furnace having been previously heated by fire manually placed within the furnace as heretofore described, the gas or fuel thus driven into the furnace chamber 12 takes fire and thereafter continues to heat the portions of the tubes 22 within the

furnace as well as the walls of the furnace. Inside of each tube or pipe 22 heretofore described is a feed screw 36 having one end entering coal hopper 14 and the other end 5 carrying a gear or sprocket wheel 38, or other equivalent mechanism. This screw serves the double function of positively feeding the solid fuel from chamber 14 through the pipe 22 and at the same time 10 causing it to travel sufficiently slowly so that in its passage through the pipe 22 substantially all of the gas contained in the solid fuel is driven off before the solid fuel has entirely completed its passage through 15 the pipe 22 and been delivered into the receptacle 24. In other words the fuel cannot travel faster than it should through the pipe 22 as would be possible with an air blast used in the absence of the screw. The 20 mechanism just described on the end of each screw 36 is geared to the corresponding mechanisms of the other screws and the whole is driven by any suitable means such for instance as a belt on a pulley 41, leading 25 to any suitable source of power, the result being that all the screws 36 are operated to force fuel through their respective pipes. In order to provide steam for mixture with coal in the hopper 14 or in the tubes 22 if 30 the character of the fuel used requires it, a pipe or chamber 40 is inserted in the top portion of the fire box 12, one end being connected through a valve 42, a funnel 44, valve 46 and a pipe 48 or any other suitable 35 means to a source of water supply, while the other end is connected through pipe 50, and valves 52 and 54 to a distributing pipe 56 entering the fuel pipes 22 heretofore described. Through the use of this mechanism water may be admitted to pipe or 40 chamber 40, converted into steam and passed into pipes 22 as the operator finds it necessary. In some convenient portion of the coal hopper 14, is a pipe 60, connected by 45 any suitable piping, not here shown, to the piping of box 40 or any other suitable source of steam and controlled by a valve 62 through which steam may be, if desired, admitted to coal within the hopper 14. 50 In the operation of the device in Fig. 1 hopper 14 is first filled with coal and the cover 18 closed down. The preliminary fire heretofore described having been built in the fire chamber 12, and it and the pipes 55 22 heated somewhat, power is applied to the pulley 41 thereby rotating screw 36. Simultaneously the injector mechanism 26-32 is started. As the mechanism thus started operates, gravity feeds the coal in the hopper 60 14 down to the entrance of the pipes 22 and into contact with the left hand ends of the screws 36. These screws take hold of the coal and slowly convey it through pipes 22. As the coal travels along these pipes it comes 65 in contact with the heated interior of the fire box 12 and the gas contained in the coal is driven off and carried along with the products, such as coke, to the chamber 34 where the gas flows, and coke and other products of the gas process drop into the 70 injector 26 through which they are driven into the furnace. As the particles of coke and the gas are thus injected into the furnace they take fire and thus provide new heat for the furnace, the pipes 22 and the 75 pipe or box 40. When once started in this manner the furnace operates continuously under its own gas as long as the hopper is supplied with coal. Whenever necessary to insure perfect gas making steam may be admitted into the pipes 22 and into the hopper 14 in the manner described. Obviously the 80 steam may be provided from an independent steam boiler wholly apart from the furnace without departing from the spirit of this 85 invention.

The device in Fig. 2 is the same as that of Fig. 1 except that a steam motor or engine 64 is substituted for the pulley 41 for driving the screw 36 within pipes 22 and 90 whatever steam is necessary within the pipes is obtained from the exhaust steam of this motor or engine 64, conveyed through a pipe 66 which preferably has a portion 68 entering the furnace chamber 12, thence entering 95 the pipes 22 at their left hand end as shown.

In Figs. 3 and 4 is shown a convenient modification of the devices of the two previous figures in which pipes 72 corresponding to pipes 22 run diagonally through the furnace, the screw 74 therein being driven by bevel gearing 76, or its equivalent operated by pulley 78 which may be, as in the case illustrated in Fig. 1, operated by a belt, or as in the case illustrated in Fig. 2, 100 by a steam engine.

In Fig. 5 an endless chain 90 passing through tube 22 and over ordinary sprockets 92 and 94 driven by any suitable source of power not shown is substituted for the conveyor screw 36 heretofore described.

The claims are:

1. In a device of the class described, a furnace, a solid fuel chamber, a pipe leading from said fuel chamber through the furnace, a screw device within the pipe for feeding and controlling the passage of solid fuel from the receptacle through the pipe at a low velocity and an injector device at the exit end of the pipe for forcing the resulting products of the fuel, both gaseous and solid, through an opening common to both into the furnace.
2. In a device of the class described, a furnace, a solid fuel chamber, a pipe leading from said fuel chamber through the furnace, a device within the pipe for feeding and controlling the passing of solid fuel from

the receptacle through the pipe at a low velocity and an injector device at the exit end of the pipe for forcing the resulting products of the fuel both gaseous and solid through an opening common to both into the furnace.

In witness whereof, I have hereunto sub-

scribed my name in the presence of two witnesses.

JAMES A. CHARTER.
